UNITED STATES PATENT OFFICE.

CHRISTIAN DIETERLE, OF CANNSTATT, GERMANY.

FIRE-GRADE ATTACHMENT.

No. 823,995.

Specification of Letters Patent.

Patented June 19, 1906.

Application filed March 6, 1901; Serial No. 50,083.

To all whom it may concern:

Be it known that I, CHRISTIAN DIETERLE, a subject of the German Emperor, and a resident of Cannstatt, Germany, have invented 5 certain new and useful Improvements in Fire-Grate Attachments, of which the following is a specification.

My present invention relates to improvements in fire-grates, and more particularly 10 to attachments therefor whereby an increased draft is produced, and consequently complete consumption of the smoke is effected.

The invention consists of the construction 15 and novel combination of parts fully described and claimed hereinafter.

In the accompanying drawings, forming a portion of this specification, Figure 1 is a plan view of a fire-grate with my attachment 20 applied thereto. Fig. 2 is a vertical transverse section of same. Figs. 3 and 4 are similar views showing a modification of the invention.

Like letters refer to like parts throughout 25 all the views.

The improved attachment consists of a plurality of plates *a*, having an arched broad upper portion and a narrow lower portion. The shoulders *b*, formed by the broad upper 30 portions of said plates, rest on the grate-bars *c*, while the narrow lower portions extend downwardly through the grate. Each plate *a* is provided with suitable projections *e*, engaging similar projections on the adjacent plates, whereby free air-spaces are produced 35 between the several plates *a*, enabling greater quantities of air to be admitted to the fire. The plates *a* are braced by means of rods *d* extending through suitable holes 40 therein and having screw-nuts or other fastening means at their opposite ends; otherwise the plates are imperforate. The advantage of the imperforate feature will be apparent when it is considered that as the current 45 of air passes upwardly into the space between the plates it cannot escape otherwise than by passing through the fuel on top of the plates, whereas if the space above were obstructed with fuel and the plates were per- 50 forated the air-current would pass from that space through the plate into another where the egress was unobstructed. This would manifestly result in an uneven combustion.

In Figs. 3 and 4 a modification is shown in 55 which the upper edge of the plates instead of being in the form of an arch is inclined

toward the central portion of the grate in such manner that the fuel thereon will have a constant tendency to shift toward the center of the grate, thus preventing the collection of 60 unconsumed fuel at the sides and the formation of a dead area.

The narrow downwardly-extending portions of the plates *a* provide means whereby the heat acting on the plate is constantly 65 transmitted downward. Moreover, a large surface is offered to the air, whereby the plates are quickly cooled and prevented from being burned.

The devices, formed of several plates 70 braced together, may be easily withdrawn from and mounted on the fire-grate—for instance, one on each side thereof—thus avoiding the necessity of effecting constructive changes. Should a plate be deteriorated, 75 the same may be easily replaced.

The form or shape of the plates *a* may be modified. Thus Figs. 1 and 2 show arched, while Figs. 3 and 4 show triangular, plates. A plurality of plates may be cast in one piece, 80 or the whole attachment may be cast in a single piece of the required length.

Having fully described my invention, what I claim, and desire to secure by Letters Patent, is—

85

1. In a device of the character described, the combination with the grate-bars, of a plurality of substantially parallel vertically-disposed plates arranged upon and at each side of the grate at an angle to the direction 90 of the draft over said grate, each of said plates having a broad upper portion resting upon and extending above the surface of the grate and a relatively narrow lower portion extending below the grate-surface and between the grate-bars, the upper edge of said plates being inclined toward the central portion of the grate, projections carried by the plates and serving to space the same apart, said plates provided with holes fitted to receive tie-rods and being otherwise imperforate, tie-rods passing through the holes in the plates, and securing-nuts thereon.

95

2. In a device of the character described, the combination with the grate-bars, of a plurality of substantially parallel vertically-disposed plates arranged upon the grate at an angle to the direction of the draft over said grate, each of said plates having a broad upper portion resting upon and extending 105 above the surface of the grate and a relatively narrow lower portion extending below 110

the grate-surface and between the grate-bars, the upper edge of said plates being inclined toward the central portion of the grate, projections carried by the plates on each side thereof, the corresponding projections on adjacent plates coinciding and serving to space the plates apart, said plates provided with holes fitted to receive tie-rods and being otherwise imperforate, tie-rods

passing through the series of plates, and securing-nuts thereon.

In testimony whereof I have hereunto set my hand in presence of two witnesses.

CHRISTIAN DIETERLE.
